UNITED STATES PATENT OFFICE.

LEON J. BARRETT, OF WORCESTER, MASSACHUSETTS.

PRUNING SHEARS.

Application filed February 27, 1925. Serial No. 12,169.

To all whom it may concern:

Be it known that I, LEON J. BARRETT, a citizen of the United States, residing at Worcester, in the county of Worcester and State of Massachusetts, have invented a new and useful Pruning Shears, of which the following is a specification.

This invention relates to a pair of pruning shears of the type in which there are two handles adapted to be grasped in the fingers of one hand and the blades are mounted on the ends of the handles and substantially in alignment with them, usually called hand pruning shears.

15 The principal object of the invention is to provide a most effective means whereby as the shears are closed together one blade will slide with respect to the other for the purpose of securing a slicing action to assist in the cutting of the limb.

20 The invention also involves a construction by which the means for moving one shear blade with respect to the other is located between them where, when they are closed, it is entirely out of the way and does not add to the bulkiness of the instrument, and in fact, serves as a stop for preventing the closing of the handles too near together.

25 The invention also involves a simple and improved means for locking the shears in closed position.

Reference is to be had to the accompanying drawings, in which

30 Fig. 1 is a side view of a pair of pruning shears constructed in accordance with this invention and shown in closed position;

Fig. 2 is an edge view of the same; and Fig. 3 is a side view in open position.

35 I have shown the invention as applied to a pair of hand pruning shears having two handles 10 and 11 and continuous with them two blades 12 and 13. The handles 10 and 11 are rounded on their outer faces to fit the hand. The blade 12 is integral with the handle 11 but the blade 13 of tool steel is separate from the handle 10, preferably being fixed on by screws 14, or in any other desired way. The handle 11 may be said to end in a solid wall 15 and the handle 10 is provided with a stop 16 adapted to abut against it to constitute a positive stop against the closing of the shears beyond the line on which they cut.

40 On the blade 12 is located a stud 17 having a head 18. This stud is fixed on the

blade by a nut on one end and a shoulder inside as is well understood, and it has a cylindrical part fitting in a slot 20 in the handle 10 or blade 13. This slot is located 45 longitudinally with respect to that blade. That is, its long dimension is substantially parallel with the cutting edge of the blade and also with the handle 10. This slot and stud constitute the pivot of the shears about 50 which the blades swing with respect to each other.

On the handle 11 is a pivot stud 21 on which is pivoted a link 22. This link is also pivoted by a stud 23 to the handle 10. 55 As shown, the link extends from a point near the pivot stud 17 on the handle 11 to a point adjacent to the outer end of the handle 10. A spring 24 having one end fixed to the handle 10 surrounds the stud 23 60 and is fixed at the other end 26 to the link 22. This spring normally acts on the link to hold the shears in the open position, shown in Fig. 3, and when the shears are closed together it is against the resistance 65 of this spring.

In operation it will be obvious that when the shears start to close from the position shown in Fig. 3, the stud 23, swinging about the stud 21, will cause the handle 10 to slide 70 backwardly and therefore will cause the blade 13 to move back toward its pivot in the direction of the slot 20. This produces a slicing cut which will materially reduce the force with which it is necessary to close 75 the shears in order to produce any good cutting effect. Also if the shears get wedged against the wood it is much easier to open them than without this arrangement.

80 This slicing action continues until the shears are entirely closed, as shown in Fig. 1, when the slot 20 is brought back so that its end engages the stud. It will be understood of course that further opening of the 85 shears from the position shown in Fig. 3 would bring the other end of the slot against the stud when they are wide open. This slot therefore constitutes at each end a stop for the further opening or closing of the 90 shears. Furthermore, when the shears are closed, as shown in Fig. 1, the link 22 is contained between the two handles parallel with both of them and preferably fills the entire 95 space between them so that it itself constitutes a stop. It will be seen also that on account of this construction the means for 100

95

105

110

sliding the blade is enclosed within the shears and adds nothing to the bulk thereof. It is obvious that when the shears are closed the stops 15 and 16 come into contact so that if any one of these stops gets worn it is likely that the others will still be effective after the shears have been used a long time.

For the purpose of locking the parts in closed position, I provide the handle 11 with a lug 30 and in the link 22 I provide a longitudinal slot 31 through which passes a screw 32 having a head 33. This screw engages on the back side in a slide 34 which has flanges that are guided in longitudinal notches 35 in the opposite edges of the link 22. On this slide there is a projecting tooth 36 which, when the parts are in closed position, can be moved along by hand to engage the lug 30, as shown in Fig. 1 and positively locks the shears against being opened. In spite of the sliding action this constitutes a positive locking means, because the parts cannot slide when in this position.

This screw head 33 can be turned with a screw driver or a jack-knife to prevent the disengagement of the locking means but when it is loosened the slide moves easily. Preferably there is a flat concave spring 37 under the head of the screw to present friction against the locking means getting out of place while using the shears.

It will be seen that this is a very simple and inexpensive shear to make, although it cannot be made to compete with the cheapest grades. It is intended to produce a high class shear without making it unduly expensive. It is well protected against the parts getting out of position, the parts are all simple, and it occupies very little space and does not require the user to learn any new method of operating. Its great advantage is that it produces a true sliding cut for slicing a limb which greatly assists in the operation of cutting it off.

Although I have illustrated and described only a single form of the invention I am aware of the fact that modifications can be made therein by any person skilled in the art without departing from the scope of the invention as expressed in the claims. There-

fore I do not wish to be limited in these respects but what I do claim is:—

1. In a hand pruning shear, the combination with a pair of crossing handles, one of them having a slot arranged longitudinally with respect to the cutting edge and the other having a stud extending into the slot, of a link extending from a point near the stud on one handle to a point near the outer end of the other handle and pivotally connected with both for causing a sliding motion of one with respect to the other when they are opened or closed, said link being located entirely in the space between the two handles, whereby it does not form a projection from the surfaces of the shears.

2. In a pair of hand shears, the combination of a pair of handles and blades fixed thereon, one handle having a locking lug, one handle having a slot and the opposite blade having a stud passing through said slot for guiding the two parts with respect to each other, of a link extending from one handle near the stud to the opposite end of the other handle and pivoted to both, and a slide on said link movable longitudinally of it and having means for engaging the lug on one of the handles to hold the parts locked in one position.

3. In a hand pruning shear, the combination with a pair of crossing handles, one of them having a slot arranged longitudinally with respect to the cutting edge and the other having a stud extending into the slot, of a link extending from a point near the stud on one handle to a point near the outer end of the other handle and pivotally connected with both said link being located in the space between the two handles, whereby it does not form a projection from the surfaces of the shears, and constituting means for preventing the handles moving toward each other beyond a certain point and the two handles also having stops thereon adapted to come into engagement at the time both handles press against the link, thus constituting two sets of stops.

In testimony whereof I have hereunto affixed my signature.

LEON J. BARRETT.
